UNITED STATES PATENT OFFICE.

JOSEPH F. VAILLANTCOURT, OF FALL RIVER, MASSACHUSETTS.

PICKER-STICK CHECK.

1,155,529.

Specification of Letters Patent.

Patented Oct. 5, 1915.

Application filed April 17, 1915. Serial No. 22,053.

To all whom it may concern:

Be it known that I, JOSEPH F. VAILLANTCOURT, a citizen of the United States, residing at Fall River, in the county of Bristol and State of Massachusetts, have invented certain new and useful Improvements in Picker-Stick Checks, of which the following is a specification.

The invention relates to a loom attachment and more particularly to the class of picker stick checks.

The primary object of the invention is the provision of a check, wherein all wear upon the picker stick is entirely eliminated, and the use of leather is avoided, yet the said stick will be checked in its movement in one direction, so as to retard its action, and thus serve as a buffer.

Another object of the invention is the provision of a check of this character, wherein the same can be readily and easily adjusted to vary the binding action thereof on the picker stick, the check being of novel form to assure the perfect working thereof.

A further object of the invention is the provision of a check of this character, wherein the guard upon the picker stick is adjustably clamped thereon so that it can be properly set for positive coöperation with the check, and can be readily and conveniently replaced when worn.

A still further object of the invention is the provision of a check of this character, which is extremely simple in construction, reliable and efficient in operation, strong, durable, readily and easily applied to the frame of the loom, and also which may be manufactured at a minimum cost.

With these and other objects in view the invention consists in the features of construction, combination and arrangement of elements, as will be hereinafter fully described, illustrated in the accompanying drawing, and pointed out in the claims hereunto appended.

In the accompanying drawing:—Figure 1, is a fragmentary perspective view of a picker stick and lay of the loom, showing the check constructed in accordance with the invention applied. Fig. 2, is a sectional view on the line 2—2 of Fig. 1. Fig. 3, is a detail perspective view of the guard for the stick. Fig. 4, is a sectional view through the same.

Similar reference characters indicate cor-

responding parts throughout the several views in the drawing.

Referring to the drawing, in detail A, designates a portion of the lay of the loom, which is of the ordinary well known construction, and B, the guideway for the picker stick C, of the usual type, while mounted on this lay is the check, herein-after fully described.

The check comprises a pair of hangers 65 in the form of blocks 5, which are secured without the guideway B, to the frame by means of bolt members 6, or any other suitable fasteners.

The blocks 5, are formed with cutaway beveled portions 7, at the points of contact with the lay, so that they will be disposed in convergent relation to each other, while spaced therefrom at the inner sides of said blocks are convexed or rounded surfaces 8, 75 to which are connected outwardly tapered resilient check arms 9, the same being adjustably fastened upon the block 5, through the medium of spaced diagonally disposed bolt members 10, which are passed there- 80 through and also through the blocks 5, and carry the usual nuts 11, so that by loosening one of the same and tightening the other of each pair the free ends of the said arms will be brought closer together, 85 thereby increasing or decreasing the checking action thereof on the picker stick, which moves between the same.

Upon the picker stick C, is mounted a guard which comprises a wearing block 12, 90 preferably formed from hard wood, the width of which is greater than the width of the picker stick, so that the said block will frictionally engage with the check arms 9, during the movement of the said stick, thereby avoiding the contact of the check arms with the picker stick to assure all wear upon the block 12, which can be readily and quickly replaced with a new one when worn. The block 12, is 100 formed with a notch 13 at its lower end to receive a clip 14, which embraces the reduced portion of the said block and the picker stick C, and through suitable openings in this clip is passed a binding bolt 15, 105 for the secure fastening of the block 12, upon the said stick, and to permit the proper adjustment of the block, as well as its removal therefrom, when it is desired to place a new one in its stead.

110

The hanger blocks 5, are preferably made from metal, while the check arms 9, are preferably made from hard wood, thereby reducing the cost in the manufacture of the 5 check and in making repairs thereto, when the parts become worn from continued use of the same.

It will be seen that the construction of the check avoids the use of leather.

10 From the foregoing it is thought that the construction and manner of operation of the check will be thoroughly understood, and therefore a more extended explanation has been omitted.

15 What is claimed is:

1. A picker stick check comprising a pair of hangers, each including a block having beveled and convex inner surfaces, means for securing the beveled surfaced portions 20 of the blocks upon the lay of a loom, for disposing the blocks in convergent relation to each other, a pair of outwardly tapered resilient checking arms having their thicker ends overlying the convexed surfaces 25 of the blocks, and duplicate means

passed through the arms and blocks and diagonally disposed with relation to each other on opposite sides of the centers of the convexed surfaces to permit the rocking of the arms thereon for the adjustment 30 thereof.

2. A picker stick check comprising a pair of resilient checking arms disposed in convergent relation to each other, hangers for the arms and having rounded contacting 35 surfaces for the arms to permit rocking of the latter thereon for changing the relative position of said arms, a wearing block on the picker stick and of greater width than the latter to engage the arms when passing 40 between the same, a reduced extension on said block, and a clip bolted on the picker stick and embracing the extension.

In testimony whereof I affix my signature in presence of two witnesses.

JOSEPH F. VAILLANCOURT.
